UNITED STATES PATENT OFFICE.

FREDERICK VARONE, OF BOSTON, MASSACHUSETTS, ASSIGNOR OF ONE-HALF TO
CHARLES F. GARLAND, OF BOSTON, MASSACHUSETTS.

SPARK PLUG.

Application filed June 24, 1920. Serial No. 391,449.

To all whom it may concern:

Be it known that I, FREDERICK VARONE, a citizen of the United States, residing at Boston, in the county of Suffolk and State 5 of Massachusetts, have invented new and useful Improvements in Spark Plugs, of which the following is a specification.

The chief object of this invention is to provide a spark plug with improved means 10 whereby a cleansing flow of air through the spark gap is induced, to cleanse the electrodes at the spark gap from deposits of carbon and other foreign matter, during the suction stroke of the engine.

15 The invention is embodied in the improvements which I will now proceed to describe and claim.

Of the accompanying drawings forming a part of this specification,—

20 Figure 1 is a top plan view of a spark plug embodying the invention.

Figure 2 is a section on line 2—2 of Figure 1.

25 Figure 3 is an enlargement of a portion of Figure 2.

Figure 4 is a view similar to Figure 3, showing the air passage closed by pressure of gases caused by the compression stroke of the engine.

30 Figure 5 is a section on line 5—5 of Figure 3.

Figure 6 is a section on line 6—6 of Figure 2.

35 Figure 7 is a sectional view, showing the shell and stopper separated, the other parts of the plug being omitted.

The same reference characters indicate the same parts in all of the figures.

40 In the drawings, 12 represents a metallic shell having a tubular externally threaded neck 13, adapted to be engaged with the wall of a combustion chamber, said neck forming a grounded electrode of annular form, the inner surface of which is formed by the bore 45 14 of the neck.

45 15 represents a conducting electrode, which has a preferably spherical head, formed on a rod 16, of conducting material. The rod 16 extends through an insulating sleeve 17 of porcelain, or other suitable material, and has a shoulder 18 bearing on an internal shoulder in the sleeve 17. The insulator has an external annular shoulder 19, which is confined by an annular nut 20, en-

gaged with an internal thread in the outer portion of the shell.

A nut 21 engaged with the threaded outer end portion of the rod 16 is seated on the outer end of the insulating sleeve. The sleeve 17, annular nut 20, and outer nut 21 55 60 constitute suitable means for securing the conducting electrode to, and insulating it from the shell. I do not, however, limit myself to the means described for this purpose.

65 The conducting electrode 15 is supported substantially concentric with the neck 13, the said electrode and a portion of the bore 14 surrounding said head, forming not only an annular spark gap, but also the walls of 70 a constricted passage portion, the function of which will appear hereinafter.

The shell is provided with an air passage communicating with the bore 14, above the spark gap, said passage including a valve 75 chamber in which a ball valve is loosely movable, said chamber having a valve seat at one side, and an air-conducting valve rest at the opposite side, the arrangement being such that the valve is adapted to be forced against its seat by gas pressure in the neck bore, so that the air passage is closed during the compression stroke of the engine, and is separated from the seat and bears on the valve rest when suction is exerted in the 80 neck bore, to permit a cleansing flow of air through the spark gap during the suction stroke.

85 The preferred construction whereby the air passage and valve chamber are provided is next described.

The shell 12 is provided at one side with a vertical rib 22, containing a tapped socket 23, extending from the upper end partly to the lower end of the rib. A horizontal duct portion 24 is bored in the shell below the socket 23, and is connected with the lower end of the socket 23 by a vertical duct portion 25 of smaller diameter than the socket. An annular shoulder or ball rest 26 is 100 formed by the intersection of the duct portion 25 with the lower end of the socket, said rest supporting a ball valve 29 and being notched to permit air to pass by the valve. The duct portion 24 enters the neck bore 14 105 at a point above the spark gap. The duct portion 24 is originally bored through the rib 22, and its outer end is subsequently

closed by a stopper 28. The duct portion 25 is bored as a continuation of the socket 23. 30 represents a tubular screw engaged with the socket 23, and having a cupped inner 5 end 31, located above the ball rest 26, said cupped end constituting a seat for the ball valve 29.

The lower portion of the socket 23, the valve rest 26, and the valve seat 31, form a 10 valve chamber, in which the valve 29 is loosely movable, the valve being supported by the rest 26 above the angular duct formed by the portions 24 and 25.

During the suction stroke of the engine 15 the valve occupies the position shown by Figures 2, 3, and 5, so that a cleansing flow of air is induced through the air passage and the neck bore 14, the air forcibly impinging upon the walls of the above-described 20 constricted passage portion, and effectively removing all accumulations of carbon, and other foreign matter, from the spark gap.

During the compression stroke of the engine, the valve 16 is held against the seat 25, so that the air passage is closed, as shown by Figure 4.

It will be seen by reference to Figure 7, 30 that the shell may be provided with the described air passage and valve chamber by a few simple operations, including the boring of the duct portion 24, the boring

and tapping of the socket 23, the boring of the duct portion 25, the grooving of the valve rest 26, the insertion of the stopper 28, and the insertion of the tubular screw 30. 35

I claim:

A spark plug comprising a tubular shell composed of an externally threaded inner portion, an enlargement above the inner portion, and a vertical rib formed on one side of said enlargement, the shell being provided with a tapped vertical socket in said rib, a horizontal duct portion extending through the lower portion of said rib to the bore of the shell, and a vertical duct portion extending from the bottom of said socket to the horizontal duct portion, said bottom being of greater diameter than the vertical duct portion, and provided with grooves, 40 so that the bottom forms an annular air-conducting valve rest; a tubular screw engaged with said socket, and having a cupped inner end located above the valve rest and forming a downwardly facing valve seat; 45 a ball valve movable vertically between said rest and seat; and a stopper closing the outer end of the horizontal duct portion, the shell being provided with a conducting electrode, and with means for securing the latter to and insulating it from the shell. 50

In testimony whereof I have affixed my signature.

FREDERICK VARONE.
